DESIGN FOR A SURFACE GRINDING MACHINE

Roger B. Kerr, Providence, R. I., assignor to
Brown and Sharpe Manufacturing Company,
Providence, R. I., a corporation of Massa-
chusetts

Application February 12, 1940, Serial No. 90,228

Term of patent 14 years

To all whom it may concern:

Be it known that I, Roger B. Kerr, a citizen of the United States, residing at Providence, in the county of Providence and State of Rhode Island, have invented a new, original, and ornamental Design for Surface Grinding Machines, of which the following is a specification, reference being had to the accompanying drawing, forming part thereof.

In the drawing:

Fig. 1 is a view in front elevation of a surface grinding machine embodying my new design; and Fig. 2 is a view in right side elevation of the surface grinding machine shown in Fig. 1. The other side of the machine is substantially like the side shown, and the rear is substantially plain.

I claim:

The ornamental design for a surface grinding machine, substantially as shown and described.

ROGER B. KERR.
